CLAIM

The ornamental design for a equidae manure/urine catcher, as shown and described.

DESCRIPTION

FIG. 1 is a perspective view showing my design for a male equidae manure/urine catcher;

FIG. 2 is a front elevation thereof;

FIG. 3 is a side elevation thereof;

FIG. 4 is a rear elevation thereof;

FIG. 5 is a top plan thereof;

FIG. 6 is a perspective view of a female equidae manure/urine catcher;

FIG. 7 is a front elevation thereof;

FIG. 8 is a side elevation thereof;

FIG. 9 is a rear elevation thereof; and,

FIG. 10 is a top plan thereof.
